UNITED STATES PATENT OFFICE.

JOB WHYSALL, JR., AND CHARLES M. MERRICK, OF NEW BRIGHTON, PA.

IMPROVEMENT IN HORSESHOE-NAIL MACHINES.

Specification forming part of Letters Patent No. 147,458, dated February 10, 1874; application filed February 4, 1874.

To all whom it may concern:

Be it known that we, JOB WHYSALL, Jr., and CHAS. M. MERRICK, of New Brighton, county of Beaver and State of Pennsylvania, have invented new and useful Improvements in Machinery for Forging or Pointing Horseshoe-Nails, Spikes, or other articles, of which the following is a full, clear, and exact description, reference being had to the accompanying drawings, which make part of this specification, in which—

Figure 1 represents a front view in elevation of the devices for forging or pointing the article desired, which constitute the subject of our invention. Fig. 2 is a cross-section of the same at the dotted lines *x x*, Fig. 1. Fig. 3 is a cross-section of the same at the dotted lines *y y*, Fig. 1. Fig. 4 is an enlarged plane view of one of the cam-wheels detached. Fig. 5 is an enlarged cross-section of part of one of the hammers detached, and Fig. 6 is an enlarged longitudinal cross-section of part of the cutter detached.

Similar letters of reference indicate corresponding parts.

It is the object of our invention to finish the horseshoe-nail or other article, and cut off and deliver the same from the machine at one revolution of the shafts; to reduce gradually the metal being acted upon, thus preserving solidity of fiber; so arranging the hammers and rollers, relatively, that the scales of the metal fall entirely clear of and are not worked into the article in process of being forged or pointed; and by a great reduction of speed, the power is advantageously applied with less wear or racking of the parts than has hitherto been attained in machines for similar purposes; and consists, first, in the combination of three hammers—two horizontal and one vertical—pivoted at the rear, and carrying dies at their outer ends, said hammers being held apart by means of a spring, and forced together by cams supported on shafts having bearings in the frame, which cams have a series of cam projections on their periphery that gradually increase in height from the one that strikes the first blow to that that gives the finishing stroke, to gradually draw down and finish the nail; second, in the combination, with these hammers and cams, of a wheel hav-

ing projecting arms bearing rollers that act in conjunction with the upper hammer, to draw and finish the face of the nail; third, in the combination, with the hammers pivoted and operated by the cams, as described, of a cutter situated on the end of one of the side hammers, and operated after the nail is finished, and while held between the hammers, by a stud on one of the cams, to cut off the nail; and, fourth, in the combination and arrangement of the actuating mechanism and the hammers with the frame and supports of the machine, as will hereafter be fully set forth.

A is a strong cast-metal frame, which carries the working parts, and rests upon and is firmly bolted to the legs *a a*. B is a metal rib to support the hammers, and is securely bolted to the frame A at *b b*. C is a cast-metal receptacle for the ends of the hammers, and is bolted to the inside of the rib B at *c*. D¹ D² D³ are the hammers, of cast or wrought metal, secured at the rear ends, by bolts, to the receptacle C, at *h h h*. The front ends of the hammers pass through the openings in the frame A, in which openings the ends of the hammers vibrate in arcs of a circle, the bolts securing them to the receptacle C forming the center. These hammers are constructed with slots at the front ends to receive the steel dies *a'*, which dies are held in place by screws passing through the hammers. (Shown at Fig. 5.) The hammers are also provided with friction-rollers *d² d² d²*. E is a rubber spring, placed between and pressing against the inside of the hammers D¹ D² D³ at their rear ends, and is secured in position by the bolt *e*, which passes through the rib B, the receptacle C, and spring E, and is provided with nuts *e¹ e²*, by which mode of securing a greater or less pressure, as may be desired, can be put upon the spring E by tightening or loosening the nut *e²*. F¹ F² F³ F⁴ are four shafts, forming a square or parallelogram upon the same plane, held in the bearings of the frame A by caps *f f*, F¹ being the main driving-shaft, the power being applied to the pulley G, or its equivalent, and the power transmitted to the other shafts by means of miter cog-wheels *g*, or their equivalent. The main shaft is also provided with a fly-wheel, H, and a wheel, I, both se-

cured by means of keys or set-screws. The wheel I has arms $i^1 i^2 i^3 i^4 i^5$, having at their extremities cylindrical rollers l , as shown clearly by the cross-section drawing, Fig. 2. The three other shafts, $F^2 F^3 F^4$, have in like manner secured to them, respectively, cam-wheels $J^1 J^2 J^3$, which wheels are each provided with cams or prominences $j^1 j^2 j^3 j^4 j^5$. These cams may be equally distant from the center of the shaft upon which they revolve; but we prefer them at irregular distances—that is to say, j^1 a little nearer than j^2 , and j^2 a little nearer than j^3 , and so on, as shown by the dotted lines, Fig. 4—the object being to gradually reduce the metal. These cam-wheels $J^1 J^2 J^3$ vibrate the hammers $D^1 D^2 D^3$ by their peripheries coming in contact with the rollers l ; and the motion of these cam-wheels and the wheel I are so timed, relatively, that the cams upon J^1 and J^2 move together, and the cams upon J^3 and the rollers upon the arms of the wheel I move together, alternating between those of J^1 and J^2 , thus delivering alternate blows and rolls upon the horizontal and vertical sides of the nail or article to be reduced or pointed. The steel dies a' of the hammers $D^1 D^2$ are so shaped and spaced as to give the required horizontal shape and width, and the steel die a' of the hammer D^3 so shaped and at such a distance from the cylindrical rollers l , when in position, as to give the required vertical thickness of the horseshoe-nail or other article forged. K is a cutter, an enlarged longitudinal cross-section of a part of which is shown at Fig. 6, and is provided with a stop-stud, M, and spiral spring O, or its equivalent. The cutter is fastened to the end of the hammer D^1 by means of screws, and vibrates with the hammer, being held out of position by the spring O until thrown forward, through the slot in the cap-piece, once at each revolution of the machine by the stud L on the cam-wheel J^3 , and is immediately thereafter returned to its position by the spring O. The stud is so arranged as to operate the cutter when the horseshoe-nail or other article being forged is finished, and when gripped between the two horizontal hammers J^1 and J^3 , the nail being free to drop from the machine when the hammers open.

The operation is as follows, viz: The machine being put in motion, the rod or other article to be forged is fed into the machine immediately after the cutter K has operated, and is partially reduced in vertical thickness between the steel die a' of the hammer D^3 and the roller l upon the arm i^1 of the wheel I; the cam j^1 of the cam-wheel J^2 , forcing down and holding in position the hammer D^3 sufficiently long to allow the roller l to pass the length desired, and immediately thereafter, by the

pressure of the spring E, forcing the hammer against the recess in the cam-wheel J^2 , and the arm i^1 of the wheel I passes out of position by the rotary motion of the shaft F^1 . The two horizontal hammers D^1 and D^2 are then, by the cams j^1 and j^1 upon the cam-wheels J^1 and J^3 , simultaneously forced against the rod, partially reducing it to the horizontal shape and width desired, and are in like manner, by the spring E, forced out of position, thus alternating the rolls and blows, until the machine has made one revolution, and finished the article being forged, when the cutter K is thrown forward or operated by the stud L, cutting off the nail, when it drops out, and the rod is immediately fed forward for another nail.

It will be evident that the relative positions of the cam-wheel J^2 and its vibrating hammer D^3 and the wheel I may be reversed; but, for reasons specified, we prefer that the cam-wheel and hammer be placed above the center line of the machine, and the wheel I below, as shown. It will also be evident that the cams upon the cam-wheel J^1 may all be equally distant from the center of the shaft upon which they revolve, and those upon J^3 at greater unequal distances than is shown, or vice versa, and that those upon the cam-wheels J^2 be equally distant from their center, and the periphery of the cylindrical rollers l at unequal distances from the center of the shaft F^1 , and produce a like gradual reduction of the metal being forged.

We claim as our invention, and desire to secure by Letters Patent—

1. The combination of the hammers $D^1 D^2 D^3$, pivoted at h , friction-rollers d^2 , and spring E, with the cams $J^1 J^2 J^3$, each having projections $j^1 j^2 j^3 j^4 j^5$ on their periphery, increasing in height from the first to the last, to gradually draw and finish the nail, as described.
2. In combination with the pivoted hammers $D^1 D^2 D^3$ and graduated cams $J^1 J^2 J^3$, the wheel I, having arms $i^1 i^2 i^3 i^4 i^5$ and drawing-rollers l , as and for the purpose set forth.
3. The combination, substantially as described, of the pivoted hammers $D^1 D^2 D^3$, friction-roller d^2 , dies a' , graduated cams $J^1 J^2 J^3$, cutter K, and stud L, as and for the purpose set forth.
4. The combination of the cams, the pivoted hammers, the drawing-rollers, and the spring with the frame Δ , supports B C, driving-shaft F^1 , and the connecting gearing, substantially as shown and described.
